UNITED STATES PATENT OFFICE.

CLARE S. JACOBS, OF DETROIT, MICHIGAN, ASSIGNOR TO TUBE PRODUCTS COMPANY, OF DETROIT, MICHIGAN, A CORPORATION OF MICHIGAN.

FEED MECHANISM FOR SWAGING MACHINES.

Application filed June 20, 1921. Serial No. 478,878.

To all whom it may concern:

Be it known that I, CLARE S. JACOBS, a citizen of the United States, residing at Detroit, in the county of Wayne and State 5 of Michigan, have invented a new and useful Feed Mechanism for Swaging Machines, of which the following is a specification.

This invention relates to rod or tube swaging machines and more particularly to feed 10 mechanisms for such machines.

The feeding of the work to such machines has heretofore been effected manually, a considerable number of men being in some cases required to overcome the resistance 15 of the machine and insure a proper advance of the work. Owing to the violent lateral vibration of the work, responsive to the hammer blows of the swaging dies of the machine, the employment of a mechanical feed, 20 although obviously highly desirable, has not been regarded as applicable to machines of this type.

It is the object of the present invention to provide mechanical means for advancing 25 the work to the dies of a swaging machine, which means will subject the work to a constant feed, and will yet permit the considerable vibratory movement of the work, transverse of its axis, which must occur in 30 response to the heavy blows of the swaging dies.

A preferred embodiment of the invention is hereinafter described and is illustrated in the accompanying drawings, wherein,

35 Fig. 1 is an end view of the die or hammer casing of a swaging machine showing the improved rod or tube feed mechanism mounted upon said casing.

Fig. 2 is a side view of the same.

40 Fig. 3 is a vertical sectional view taken upon line 3—3 of Fig. 2.

Fig. 4 is a vertical section taken upon line 4—4 of Fig. 1, and showing the drive gearing for the feed mechanism.

45 Fig. 5 is a vertical section on line 5—5 of Fig. 1, showing the work advancing roller.

In these views the reference character 1 designates a cylindrical casing, in which is 50 housed the hammers or other work-fashioning elements of a rod or tube swaging machine. One end 2 of the casing 1 is hinged, as indicated at 3, to provide for access to said mechanism (not shown) within the casing. The normal position of said hinged

end, shown in the drawings, is maintained by a headed pin 4 engaging in registering lugs 5 and 6 respectively formed upon said end and upon the body of the casing. The closure 2 is formed adjacent its top and bottom with integral horizontal ribs 7, which are flanged toward each other adjacent the free edge of said closure, as indicated at 8, and a gear casing 9 is secured by bolts 10 to said flanges. A pair of horizontal shafts 60 11 are journaled above and below the axis of the casing 1, equidistantly from said axis, said shafts being journaled at one end in a wall of the casing 9 and at their other ends in a bearing plate 12 secured to the ends of 70 the ribs 7. Upon said shafts there are respectively splined two pairs of rollers 13, the opposed faces of each pair being peripherally beveled for engagement with the work, indicated at 14. Also the rollers of 75 each pair are urged yieldably toward each other by springs 14 coiled upon the shafts 11. Said springs maintain engagement of the beveled faces of the rollers 13 with the work, and insure that the rollers will frictionally grip the work with sufficient firmness to insure the desired actuation of the work by the rollers. Each shaft 11 has collars 15 respectively mounted upon its end portions as abutments for the springs 14, 80 and in order to properly regulate the compression of said springs, it is preferred to adjustably engage said collars with the shafts 11 by means of screw-threads. The casing 9 encloses a drive gearing for the 90 shafts 11, which gearing comprises two worm gears 16 and a worm 17 arranged between and driving both of said gears. Said worm is fast upon a drive shaft 18, transverse to the two shafts 11, and journaled in 95 bearings 19 formed integrally with opposed walls of the casing 9. Said shaft projects from the casing in the direction from which the work is fed and carries upon the portion thus projecting a pulley 20 driven 100 through a belt 21 from any suitable source of power.

In the operation of the described feed mechanism a gradual and powerful rotation of the feed rollers 13 is secured through employment of the worm and worm wheel gearing. Under impact of the swaging hammers the work as it advances is subjected to a heavy vibration transversely of its length, and the engagement of the beveled 110

feed rollers 13 with the work is such as to provide for this unavoidable vibration. Thus, upon a movement of the work to the right or left (see Fig. 1) the two feed rollers at one side of the work will recede and the two at the other side will advance so as to conform to the shifting of the work without interrupting or even varying the forward advance of the work to the swaging hammers. In case of a vertically acting vibratory movement of the work, one of the pairs of rollers 11 will spread apart to accommodate such movement and the rollers of the other pair will approach each other sufficiently to maintain the desired frictional driving pressure upon the work. The two described movements of the rollers will be combined when the vibration is in some radical direction other than vertical or horizontal.

Thus it is seen that the invention accomplishes a mechanical feed of the work despite the violent vibratory action of the work responsive to the swaging hammers, and the feed thus provided is much less expensive and a great deal more uniform and reliable than any feed depending upon manual effort. Furthermore, the violence of the vibratory movement is held in check by the coiled springs 14 and the swaging machine is consequently enabled to accomplish a more efficient and satisfactory operation upon the work.

What I claim is:

1. In a rod or tube feed mechanism, the combination with two parallel shafts, of two opposed pairs of feed rollers respectively splined upon said shafts, springs urging the rollers of each pair toward each other, and a common driving means for said shafts.

2. In a rod or tube feed mechanism, the

combination with two parallel shafts, of two opposed pairs of feed rollers splined upon said shafts, the opposed faces of each pair of rollers being peripherally beveled to engage the work, springs urging the rollers of each pair toward each other, and a common driving means for said shafts.

3. In a rod or tube feed mechanism, the combination with two parallel shafts, of two opposed pairs of feed rollers respectively splined upon said shafts, springs urging the rollers of each pair toward each other, worm-wheels mounted oppositely upon said shaft, and a worm between said worm-wheels driving both of the same.

4. In a rod or tube feed mechanism, two opposed pairs of work engaging rollers, the rollers of each pair being movable independently in the direction of their common axis, means urging the rollers of each pair yieldably toward each other, and a common drive means for said rollers.

5. In a rod or tube feed mechanism for swaging machines, the combination with a casing for the swaging mechanism, said casing having a hinged end member through which the work is fed, of feed mechanism mounted upon said end member for automatically advancing the work.

6. In a rod or tube feed mechanism for swaging machines, the combination with a casing for the swaging mechanism, said casing having a hinged end member through which the work is fed, of feed mechanism mounted upon said end member for automatically advancing the work, said feed mechanism being yieldable to afford the work a lateral movement in any direction.

In testimony whereof I sign this specification.

CLARE S. JACOBS.
